UNITED STATES PATENT OFFICE.

JOHN ERNEST TYTLER AND WILLIAM HENRY BOWKER, OF MANCHESTER,
ENGLAND.

THREAD-GUIDE FOR SPINNING-FRAMES.

No. 806,024.

Specification of Letters Patent.

Patented Nov. 28, 1905.

Application filed February 25, 1905. Serial No. 247,374.

To all whom it may concern:

Be it known that we, JOHN ERNEST TYTLER, draftsman, a resident of Manchester, (whose post-office address is 26 Mellor road, 5 Longsight, Manchester,) and WILLIAM HENRY BOWKER, buyer, a resident of Manchester, (whose post-office address is Holly Bank, Highfield, Gorton, Manchester,) in the county of Lancaster, England, subjects of the King of 10 Great Britain and Ireland, have invented new and useful Improvements Relating to the Thread-Guides of Spinning, Twisting, and Like Frames, of which the following is a specification.

15 This invention relates to improvements in thread-guides for spinning, twisting, and like frames for yarns, the object being to provide a guide of improved construction, easy to produce, and capable of ready adjustment in relation to the spindle and one which when adjusted is locked so far as to be immovable in any direction.

Figure 1 is a side elevation of a thread-guide constructed in accordance with our invention attached to one of the longitudinal rails of a spinning or like frame, showing the device both in the operative and non-operative positions; Fig. 2, a front elevation of same with the guide in the non-operative position; Fig. 3, a plan; and Fig. 4, a front elevation, partly in section, of the guide in the operative position.

In the drawings, *a* represents the longitudinal rail of a spinning or like frame, to which 35 what are generally termed the "thread-boards" *b*, of iron or wood, are attached by bolts *c* or the like and hinged plates *d*. The rail *b* is held in the position indicated in Fig. 1 by stops or projections on the rail *a* or on 40 the end frames of the machine of which the rail *a* forms a part. These parts are of ordinary construction. In carrying out our invention we secure to the rail *b* or in some cases direct to the rail *a* a metallic thread-rail *e*, 45 preferably one for each spindle, so that they may be moved about their hinges *f* independently of each other. Securing-plates *g* form part of the thread-rails and are bolted or otherwise secured to the rail *b* by bolts *h*, the

bolt-holes being slotted to allow of longitudinal movement on the supporting-rail for adjusting purposes. The thread-rail *e* and securing-plate *g* are preferably made of sheet metal. The thread-rails *e* are each kept in a more or less horizontal position by lugs *g'*, 55 forming part of the plates *g*.

The parts just described are of ordinary construction and similar to the arrangements described in our previous application for United States Patent, Serial No. 194,021, 60 filed February 17, 1904.

The special feature of our invention consists in turning over the end of each thread-rail *e*, so as to form a horizontal portion *e'*. From this portion we turn upward another 65 portion *e''*, which is slotted at *i* to enable a grooved screw-nut *j* to be passed therethrough and screwed onto the end of the thread-wire *k*. The nut *j* is grooved at *j'*, such groove embracing the upturned portion 70 *e''* and while allowing the nut to be turned round by a spanner or other tool prevents it moving longitudinally. By this means the thread-guide wire *k* can be adjusted longitudinally, so as to bring the guide-eye *k'* over 75 the center of the spindle. The guide-wire is prevented from turning by being flattened at *l* and passed through a correspondingly-shaped hole *l'* in the thread-rail *e*.

What we claim as our invention, and desire to secure by Letters Patent, is—

A metallic hinged thread-guide for spinning, twisting and like frames provided with a turned-under portion on its bottom side, a turned-up portion projecting therefrom a 85 grooved nut adapted to embrace the turned-up portion and a screwed thread-guide wire flattened in cross-section and passed through a hole of similar shape in the thread-rail and provided with a screwed end to engage with 90 the grooved nut substantially as described.

In testimony whereof we have hereunto set our hands in the presence of two witnesses.

JOHN ERNEST TYTLER.

WILLIAM HENRY BOWKER.
